(57) **CLAIM**

The ornamental design for a game controller thumbstick set, as shown and described.

DESCRIPTION

FIG. 1 is a front, right and bottom perspective view of game controller thumbstick set showing my new design;

FIG. 2 is a rear, left and top perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken lines shown in the figures are for the purpose of illustrating portions of the game controller thumbstick set that forms no part of the claimed design.
